US00D873476S

(12) **United States Design Patent** (10) Patent No.: **US D873,476 S**
(45) Date of Patent: **** Jan. 21, 2020**

(54) **BEZEL FOR AUTOMOBILE HEADLAMP**

(71) Applicants: **HYUNDAI MOTOR COMPANY, Seoul (KR); KIA MOTORS CORPORATION, Seoul (KR)**

(72) Inventors: **Flores Rogelio, Irvine, CA (US); Tony Chen, Irvine, CA (US); Bradley Arnold, Irvine, CA (US)**

(73) Assignees: **Hyundai Motor Company, Seoul (KR); Kia Motors Corporation, Seoul (KR)**

(**) Term: **15 Years**

(21) Appl. No.: **35/505,800**

(22) Filed: **Apr. 3, 2018**

(80) **Hague Agreement Data**

Int. Filing Date: **Apr. 3, 2018**

Int. Reg. No.: **DM/100671**

Int. Reg. Date: **Apr. 3, 2018**

Int. Reg. Pub. Date: **Oct. 5, 2018**

(51) **LOC (12) Cl. 26-05**

(52) **U.S. Cl. D26/139**
